UNITED STATES PATENT OFFICE.

DAVID C. KLAUSMEYER, OF CINCINNATI, OHIO, ASSIGNOR TO THE CINCINNATI BICKFORD TOOL COMPANY, OF OAKLEY, CINCINNATI, OHIO, A CORPORATION OF OHIO.

ACCESSIBLE TWIN-LEVER GEAR SHIFT FOR DRILL HEADS.

Application filed September 18, 1924. Serial No. 738,440.

This invention relates to radial drilling machines and more particularly to means for selectively meshing certain speed-change gears which of necessity are located in an 5 inaccessible position in the drill-head.

Radial drills, as commonly constructed, comprise a base, an upright column, and a laterally projecting arm upon which is slidably mounted a drill-head carrying a vertically disposed drill-spindle. Power to rotate the drill-spindle and feed it vertically 10 may be provided by a motor or other prime-mover located on the base at the foot of the column, and the power therefrom may be transmitted through suitable mechanism to a shaft journaled lengthwise of the radial arm and thence through suitable change-gear mechanisms to the drill-spindle.

As is well understood by those skilled in 20 the art, it is essential that means be provided for regulating the speed of rotation of the drill-spindle inasmuch as the varying diameters of the drills and taps being used and the nature of the work being operated 25 on, each present working conditions which require different speeds of rotation of the spindle to produce maximum efficiency in operation.

To provide these various speeds it has 30 heretofore been customary to locate adjacent the prime-mover, a change-gear mechanism capable of transmitting about six or eight different speeds from a single speed received from the prime-mover. The differences in 35 ratio afforded by this so-called "speed-box" control are necessarily small since there is considerable mechanism actuated thereby and great differences in ratio would effect abrupt changes and cause strains that would 40 be detrimental to the parts.

Coarser changes are provided by a change-gear mechanism located in the drill-head. These latter change-gears are commonly known as the "back-gears" and usually provide 45 four speed changes which multiply the number of speeds provided by the speed-box. Inasmuch as only the spindle is actuated by the back-gears the speed changes provided therein may be materially greater than those 50 provided in the speed-box.

The back-gears are preferably located in the upper end of the drill-head, intermediate the horizontal arm shaft and the upper end of the spindle and comprise a plurality 55 of fixed and shiftable gear-units. Inasmuch

as these gears are expensive to manufacture and furthermore as in operation they attain momentum which has to be overcome when the direction of rotation of the spindle is reversed, it is desirable that the required 60 speed changes be effected with as few gears as possible.

Heretofore, great difficulty has been experienced in the shifting of the back-gears. 65 As before stated these gears are located in an inaccessible position in the upper end of the drill-head and therefore in large drills when the arm is adjusted to a position adjacent the upper end of the column not only 70 are the gears inaccessible but any shifting means therefor which is located adjacent the gears is also out of the operator's reach which necessitates the use of a ladder, box or the like to enable him to reach the gear-shifters thereby to make the necessary speed 75 changes.

Various devices have heretofore been provided for the shifting of these back-gears but they are all more or less inconvenient 80 or inaccessible and none is entirely satisfactory. It is believed that the most nearly satisfactory device heretofore provided is that disclosed in applicant's Patent No. 1,204,668 of which the present invention is 85 an improvement. Applicant's prior construction, however, has its shortcomings inasmuch as it admits of only three speed-changes and due to the nature of the shifting mechanism requires eight gears and four clutches to produce the three speed-changes. 90

This invention has for an object to provide improved means, conveniently accessible to the operator, for shifting the back-gears in a radial-drill head.

A further object of the invention is to 95 provide an improved back-gear shifting mechanism conveniently accessible to the operator and which is so constructed and arranged that at least four speed changes may be effected with a minimum number of 100 gears.

A still further object of this invention is to provide, in connection with two shiftable gear-units of radial drill back-gears, independent shifting devices for said gear-units, 105 each device having its own controlling elements, said controlling elements being located easily accessible to the operator and having an operative connection with the remote and inaccessible gear-units. 110

Other objects and advantages will be in part indicated in the following description and in part rendered apparent therefrom in connection with the annexed drawings.

To enable others skilled in the art so fully to apprehend the underlying features hereof that they may embody the same in the various ways contemplated by this invention, drawings depicting a preferred typical construction have been annexed as a part of this disclosure and, in such drawings, like characters of reference denote corresponding parts throughout all the views, of which:—

Fig. 1 is a vertical section of a drill-head embodying the present invention. Fig. 2 is a horizontal section on the line 2—2 of Fig. 1. Fig. 3 is a detail section substantially on the line 3—3 of Fig. 2. Fig. 4 is a detail front view of a portion of the drill-head showing the gear-shifting arms carried thereby and the rack-bars actuated by the arms. Fig. 5 is a section on the line 5—5 of Fig. 4.

Referring more particularly to the drawings the invention is disclosed as embodied in a drill-head indicated generally as 1. This drill-head is formed with guide-ways 2 and 3 adapted to slide upon a suitable radial-arm, (not shown) as is common to this type of machine-tool. A variable speed-shaft 4 is journaled lengthwise of the arm and carries two bevel-gears one only, of which is shown. These gears are adapted to drive, in opposite directions, a similar bevel-gear 5 fixed upon a vertical shaft 6 journaled in the drill-head. Inasmuch as the means for rotating the shaft 4 at varying speeds and the means for reversing the direction of rotation of the shaft 6 form no part of this invention detail illustration and description thereof is deemed unnecessary.

Slidably secured to the shaft 6, as by means of splines 7, is a gear-unit 8 provided with gears 9 and 10. These gears are adapted selectively to be brought into mesh with gears 11 and 12 provided by a non-translatable gear-member 13 secured upon an intermediate shaft 14 journaled in bearings *c* and *d* in the drill-head. The gear-member 13 may be formed as a unit or, for convenience of manufacture, it may be made in separate pieces *a* and *b* as shown in Fig. 1. The shaft 14 also carries a small gear 15 and the gear-member 13 provides a gear 16, both later to be referred to.

Rotatably journaled in the drill-head 1 is a sleeve 17 within which is splined, for vertical movement, the usual drill spindle 18 adapted to carry at its lower end a drill 19, or other suitable tool. Thus rotation of the sleeve 17 will, through the spline connection 20, likewise effect rotation of the spindle 18 and still permit the spindle to be moved vertically in the sleeve.

To the sleeve 17 is slidably secured, as by

means of splines *e* and *f* a gear-unit 21. This gear-unit provides a gear 22, adapted upon one movement of the unit to be engaged with the gear 16 and a series of clutch-teeth 23 adapted in another movement of the unit to engage similar clutch-teeth 24 formed in a gear-member 25 loosely journaled coaxial with the sleeve 17.

The member 25 is also formed with a gear 26 maintained permanently in mesh with the gear 15. From the foregoing it will be seen that by selectively meshing the gears 9 and 11 or 10 and 12 any given speed of the shaft 6 may be converted into two speeds in the shaft 14. Likewise each of these two speeds may be converted into two different speeds in the spindle-driving sleeve; this last conversion being selectively effected by shifting the gear-unit 21 in one direction lengthwise of the spindle to mesh the gears 16 and 22 or in the opposite direction to cause power to flow from the shaft 14 through gears 15 and 26 and clutch-teeth 23 and 24 to the driving-unit 21.

The gear-units 8 and 21 may be shifted into either of their operative positions to effect the desired spindle speed by an improved means now to be described. Fulcrumed intermediate its ends upon a shaft 27, secured in the upper part of the drill-head, is a lever 28 which carries at one end a fork 29 embracing the shiftable gear-unit 8. The opposite end of the lever 28 is formed as gear-segment 30 which is engaged by the teeth 31 of an endwise movable gear-shifting rod 32. A lever 33, of the second order, is also fulcrumed upon the shaft 27 and carries, intermediate its ends, a gear-shifting fork 34, engaging the gear-unit 21. The lever 33 is also formed with a gear-segment 35 which meshes with the teeth 36 of a gear shifting rod 37, similar to the rod 32. The rods 32 and 37 extend downwardly from the segments 30 and 35 beside the drill-head and are provided at their lower ends with rack-teeth 32^a and 37^a respectively. Within ears *g* and *h*, provided by the lower portion of the drill-head, is journaled a short shaft 38, to which is secured, as by a pin 39, a gear 40. This gear is maintained permanently in mesh with the teeth 37^a of the rod 37, and may be rotated to shift the rod vertically by means of a hand-lever 41 also secured to the shaft 38. A gear 42, similar to the gear 40, is loosely journaled upon the shaft 38 and permanently meshes with the teeth 32^a of the rod 32. A hand-lever 43 is formed integral with the gear 42 and affords means for rotating the latter to effect vertical movement of the rod 32.

From the foregoing it will be seen that by manipulation of the levers 41 and 43 the rods 32 and 37 may be shifted vertically and that these rods, acting upon the levers 28 and 33 and the gear-shifting forks 29 and 34

will cause the gears 9 and 11, 10 and 12, 16 and 22 and clutch-elements 23 and 24 selectively to be engaged to effect any one of four available speed-changes in the drill-spindle.

To maintain the teeth 31 and 36 in engagement with the segments 30 and 35 and to prevent lateral displacement of the rods 32 and 37, these rods are preferably guided 10 at their upper ends by means of the walls *i*, *j* and *k* of a stud 44 carried by a bracket 45 secured to the drill-head. The lower ends may be similarly guided by a bar 46 secured to the ears *g* and *h*.

15 It is to be understood that the levers 41 and 43 are carried at the lower end of the drill-head and therefore are easily accessible to the operator in all of the adjusted positions of the arm and drill-head.

20 To prevent accidental shifting of the levers 28 and 33 and the gear-units 8 and 21 the levers are provided with sectors 28^a and 33^a respectively. These sectors are provided with indentations 28^b and 33^b adapted 25 to be engaged by spring detents 28^c and 33^c.

From the foregoing it will be seen that there has been provided an improved back-gear mechanism comprising only eight gears 30 that produce four speed-changes and also novel means readily accessible to the operator for shifting the gear-units.

Without further analysis, the foregoing will so fully reveal the gist of this invention that others can, by applying current knowledge, readily adapt it for various utilizations by retaining one or more of the features that, from the standpoint of the prior art, fairly constitute essential characteristics of either the generic or specific aspects of this invention and, therefore, such adaptations should be, and are intended to be, comprehended within the meaning and range of equivalency of the following claims.

45 Having thus revealed this invention, I claim as new and desire to secure the following combinations and elements, or equivalents thereof, by Letters Patent of the United States:

50 1. In a machine tool, in combination, a plurality of shiftable gear-units; a gear-shifter engaging each of said gear-units;

gear-shifting levers of the first and second class, respectively, journaled coaxially in said machine tool between said gear units, 55 each of said levers being formed integral with a gear-segment and each lever wholly supporting one of said gear shifters; actuating hand-levers located remote from gear-shifting levers; and operative connections 60 between said hand levers and said gear-shifting levers whereby the latter are actuated by the former, each of said connections including a rack-bar engaging the gear-segments on said gear-shifting levers and 65 operative connections between said actuating levers and said rack bars.

2. A gear-shifting mechanism combining a plurality of shiftable gear-units; a gear shifter engaging each of said gear units; 70 gear-shifting levers fulcrumed upon a common axis and each carrying one of said gear-shifters; a gear-segment carried by each of said levers; a translatable rack-bar meshing with each of said gear segments; 75 means to translate said rack-bars; and a stationary stud located at the side of said rods remote from said gear segments, said stud being formed with transverse walls engaging transverse surface of said rack-bars 80 to maintain said rack-bars in contact with said gear-segments and to prevent lateral movement of said rack-bars.

3. In a drill-head, in combination, a drive-shaft; a spindle; a change-speed mechanism 85 operatively connecting said drive-shaft with said spindle and including two shiftable gear-units; two levers fulcrumed adjacent said change-speed mechanism and each connected with one of said shiftable gear-units, 90 each of said levers being provided with a toothed sector and a plain sector provided with an indentation; a rack-bar meshing with said toothed sector; means operable from a point remote from the change-speed 95 mechanism for shifting said rack-bar to oscillate said levers and shift said gears; and spring detents adapted to engage said indentations to prevent accidental movement of said levers.

In witness whereof, I hereunto subscribe my name.

DAVID C. KLAUSMEYER.
